TRACE AND TUG BUCKLE.

1,081,804.

Specification of Letters Patent.

Patented Dec. 16, 1913.

Application filed February 24, 1913. Serial No. 750,323.

To all whom it may concern:

Be it known that I, NELS L. ANDERSON, a citizen of the United States, and a resident of Spearfish, in the county of Lawrence and State of South Dakota, have invented a new and Improved Trace and Tug Buckle, of which the following is a full, clear, and exact description.

The invention relates to buckles for engaging a trace and a hame tug.

It is a design of the invention to provide a buckle for the mentioned purpose, of light construction and simple form, adapted to adjustably receive the trace therein and permit of the ready adjustment of the trace, to shorten or lengthen the same.

The invention will be particularly explained in the specific description herein-after to be given.

Reference is to had to the accompanying drawings forming a part of this specification in which similar characters of reference indicate corresponding parts in all the views.

Figure 1 is a sectional plan view showing a buckle embodying my invention applied to a trace and tug, fragments of the trace and tug being indicated, the buckle being adapted for single light harness and express harness; Fig. 2 is a rear end view with the trace in section, on the line 2—2 of Fig. 1; Fig. 3 is a perspective view of the trace frame of the buckle; Fig. 4 is a plan view of a buckle having the tug frame thereof slightly varied to adapt the buckle for light double driving harness; and Fig. 5 is a similar view showing the tug frame formed to adapt the buckle for heavy team harness.

The buckle comprises two frame parts on which the various appurtenances are integral and rigid, and for convenience and in the interest of clearness, I will designate one frame as the tug frame, and employ the numeral 10 with exponents to indicate the various elements of the tug frame; the other frame I designate the trace frame and will employ the numeral 11 and exponents to indicate the elements of said frame. Thus the tug frame comprises side arms 10, which are joined at the front at one face of the buckle, by a cross bar 10^a adapted to receive the loop *a* of the tug A. The side arms extend to the opposite face of the buckle, preferably in curved form, as at 10^b, as best seen in Fig. 1, the ends of the portions 10^b being joined

by a cross bar 10^c, which I term the rear cross bar, and which lies at the opposite face of the buckle from the bar 10^a, at a point rearward of the latter, the two cross bars being spaced laterally a sufficient distance to accommodate between them a trace B, which is passed lengthwise through the buckle. The cross bar 10^c has a rearward extension in the form of a plate 10^d, for a purpose hereinafter explained.

The trace frame is received within the tug frame between the side arms 10^a, and is adapted to slide and to rock therein. The trace frame comprises side arms 11 that range diagonally of the buckle, crossing the arms 10^a of the tug buckle, at the portions 10^b thereof. Pins 10^e project from the inner faces of the arms 10^b of the tug frame toward each other at points between the front and rear ends of the said arms, said pins overlying the side arms 11 of the trace frame. The front ends of the side arms 11 of the trace frame are joined by a cross bar 11^a at the face of the buckle on which the rear cross bar 10^c of the tug frame is located and lies in front of and in line with the latter. On the cross bar 11^a is a pin 11^b, projecting toward the opposite face of the buckle and adapted to enter one of a series of holes *b* in the trace B. At the opposite end of the arms 11 of the trace frame a cross bar 11^c may join said arms for giving strength. The trace frame is provided at the sides at the rear end of the buckle with pins 11^d, which extend in the opposite direction to the pin 11^b, having their bases adjacent to the cross bar 11^c. The ends of the pins 11^d project to a bearing against the inner face of the extension 10^d of the rear cross bar 10^c of the tug frame, and they receive the trace B between them.

When in use it will be obvious that a pull on the tug A will exert a forward pull on the side arms 10^a of the tug frame, and the front edge of the cross bar 10^c of the tug frame will engage the opposed edge of the front cross bar 11^a of the trace frame, and thus through the pin 11^b will exert a pull on the trace B. At the same time the inner face of the extension 10^d will be pressed against the ends of the pins 11^d, which project from the opposite face of the trace frame, at the rear of the buckle, so that the tug frame will engage the trace frame at the front against the cross bar 11^a, and at the rear by 110

pressure against the pins 11^a, and the two frames will be firmly pressed against each other by the draft strain, whereby to distribute the strain on the buckle.

5 To adjust the trace in the buckle, the trace is moved forwardly, that is, in the direction of the arrow shown at the line 2—2 (Fig. 1), which will cause the trace frame to slide in the tug frame, and the ends of the pins 10 11^a will move forwardly along the inner face of the plate extension 10^a. The trace frame may now readily be rocked, as indicated in dotted lines in Fig. 1, to withdraw the tongue 11^b of the trace and permit the trace 15 to be moved forwardly for engagement of the pin 11^b with a rearward hole *b*.

The described construction is particularly adapted for express harness and single light harness. In the form shown in Fig. 4, the 20 tug frame is very slightly modified to adapt the buckle for use on light, double driving harness. The tug frame, Fig. 4, is in all respects essentially the same as shown in Figs. 1 and 2, except that the rearward extension or plate 10^f, which corresponds with 25 the extension 10^a in Figs. 1 and 2, is provided at the rear end with a loop 10^g, necessary in double light harness. The elements 30 of the buckle, other than 10^f and 10^g, are indicated in Fig. 4 by the same characters as in Figs. 1 to 3, because their forms are the same in all respects.

In Fig. 5, I have shown a tug frame further modified, only to the extent of adapting the buckle to heavy team harness, 35 for which purpose the several straps of the harness require three loops 10ⁱ, 10^j and 10^k, the loop 10^j being at the rear and corresponding with the loop 10^g in Fig. 4, and 40 the loops 10ⁱ and 10^k being at right angles to the loop 10^j, and at opposite sides. The several loops are formed in an enlargement 45 10^h extending at three sides of the extension 10^a, which is the same as shown in Figs. 1 and 2.

Having thus described my invention, I claim as new, and desire to secure by Letters Patent:

1. A buckle, comprising a tug frame, and 50 a separate trace frame slidable and rockable in the tug frame, each frame having side arms, the respective arms crossing, the tug frame having pins projecting from the inner faces of the side arms toward each other at 55 points between the ends of the arms and overlying the arms of the trace frame, said arms of the tug frame being joined at their rear ends at one face of the buckle by a cross bar, and the opposite ends of the arms being joined by a second cross bar located forwardly of the said rear cross bar and lying 60 in a plane at one side of the plane of the first cross bar to afford a passage for a trace through the buckle between the said cross bars, the front cross bar being adapted

to receive a tug strap; the arms of the trace frame having a front cross bar at the end adjacent to the rear cross bar of the tug frame and in front of said rear cross bar, the said cross bar of the trace frame having 70 a pin at substantially right angles thereto and projecting toward the opposite side of the buckle to engage a trace, the trace frame having a second cross bar at the opposite end rearward of the rear cross bar of the 75 tug frame and at the opposite side of the buckle, and pins extending in the opposite direction to the first pin and spaced apart to accommodate the trace between them, the rear cross bar of the tug frame having a 80 plate extending rearwardly therefrom, the inner side of said plate lying against the ends of the spaced pins on the trace frame.

2. A buckle, comprising a tug frame, and a separate trace frame slidable and rockable 85 in the tug frame, each frame comprising side arms and the arms of the respective frames crossing, the tug frame having a cross bar at one face of the buckle, at the front end of the latter, to receive a tug, and a cross bar at the opposite face of the buckle, at the rear ends of the arms, said cross bars being separated transversely to accommodate a trace, the side arms of the trace frame having a cross bar at one face 90 of the buckle in front of and adjacent to the rear face of the tug frame, said cross bar of the trace frame having a pin projecting toward the opposite face of the buckle to engage a trace, and there being a pair of 95 spaced pins on the trace frame at the end opposite the first mentioned pin and projecting in the opposite direction to the latter, the tug frame having portions to bear against the ends of the said spaced pins, 100 and there being means on the tug frame overlying the arms of the trace frame and slidably engaging said arms, at points between the ends of the latter.

3. A buckle, comprising a tug frame having side arms, and a separate trace frame slidable and rockable in the tug frame and having side arms for crossing the arms of the tug frame, there being means on the arms of the tug frame, at the inside thereof, 115 between the ends of said arms overlying the arms of the trace frame to engage the latter, the tug frame having a front cross bar for a tug at one face of the buckle, and a rear cross bar at the opposite face of the buckle, 120 a cross bar on the trace frame disposed in front of and adjacent to the rear cross bar of the tug frame and having a pin projecting therefrom toward the opposite face of the buckle to engage a trace, the tug frame 125 having two pins located thereon at the rear end of the buckle, at the sides of the latter, the pins projecting in the opposite direction from that of the first pin, and the tug frame having at the rear of the rear cross bar a 130

rear extension to bear against the ends of the second mentioned pins, and slidably engaging the latter.

4. A buckle, comprising a tug frame having side arms, and a separate trace frame slideable and rockable in the tug frame, and having side arms that cross the arms of the tug frame, the tug frame having a front cross bar for a tug at one face of the buckle
5 and a rear cross bar at the opposite face of the buckle, the trace frame having a cross bar in front of and adjacent to the rear cross bar of the tug frame provided with a pin projecting toward the opposite face
10 of the buckle to engage a trace, and there
15

being spaced pins on the trace frame at the rear of the buckle, the pins projecting in the opposite direction from that of the first pin, and the tug frame having at the rear cross bar a rearward extension to bear 20 against the ends of the second mentioned pins, and slidably engage the latter.

In testimony whereof I have signed my name to this specification in the presence of two subscribing witnesses.
